UNITED STATES PATENT OFFICE.

LOUIS W. BAUER AND JOHN E. DAVIS, OF WASHINGTON, DISTRICT OF COLUMBIA, AS
SIGNORS OF ONE-THIRD TO LESTER WOLFE, OF NEW YORK, N. Y.

ROPE AND CORD FASTENER.

1,333,375.

Specification of Letters Patent.

Patented Mar. 9, 1920.

Application filed April 15, 1919. Serial No. 290,167.

To all whom it may concern:

Be it known that we, LOUIS W. BAUER and JOHN E. DAVIS, citizens of the United States, residing at Washington, in the District of Columbia, have invented certain new and useful Improvements in Rope and Cord Fasteners, of which the following is a specification.

Our invention relates to cord or rope fasteners, and particularly to devices of this character adapted to securely hold both bights of a looped cord or rope.

The object of our invention is to provide a rope or cord fastener particularly adapted for securing the cord about the top of a mail sack or pouch which shall permit the cord to be quickly drawn tight to close the sack and which will securely hold the cord to maintain the pouch closed. A further object of our invention is to provide a device as mentioned equipped with means whereby should one bight of the loop be partially withdrawn therefrom the other bight will be drawn within the device a corresponding amount, thereby maintaining the same contracted size of the loop. A further object of our invention is to provide a device as mentioned equipped with means whereby a padlock may be used to secure the parts in locking position to prevent unauthorized tampering with the contents of the pouch. A further and particular object of our invention is to provide a device of the character under consideration which shall be of few parts, simple of construction, and of low cost to manufacture. Other objects will appear hereinafter.

With these objects in view, our invention consists generally in a peculiarly tapered housing through which both bights of the looped cord or rope are adapted to be passed, a rotary member adapted to wedge said bights against the opposite walls of the housing, and means for holding said rotary member in wedging position. Our invention further consists in a device as mentioned in which said rotary member is mounted upon a slide having limited movement within said housing and equipped with means for receiving a locking device, such as a padlock, to hold the rotary member in

wedging position. Our invention further consists in a device of the character under consideration comprising a tapered housing, a slide mounted for limited movement therein, a rotary member carried by said slide and adapted in one position to clamp the bights of the rope against the opposite walls of the housing, and said housing being provided with means to prevent accidental retraction of the rotary member and slide such as from shaking or jarring.

Figure 1 is a plan view of a clamping device embodying our invention in its preferred form.

Fig. 2 is a vertical, longitudinal section thereof.

Fig. 3 is a horizontal section on substantially the line 3—3 of Fig. 2.

Fig. 4 is a transverse section on the line 4—4 of Fig. 3, and

Fig. 5 is a perspective view of the slide. Referring now to the drawings, 1 indicates a tapered housing which is mounted upon a base plate 2. The base plate is stamped from sheet metal and is provided at one end with an upturned flange 3 provided with apertures 4, 4 to receive the bights of a rope or cord 5. The longitudinal edges of the plate 2 are bent upon the opposite side of the plate from the housing 1 forming flanges 6 to hold the usual card used in conjunction with mail bag fastenings, and at the opposite end from the flange 3 the plate is formed with a transverse flange 7 forming a stop for said card.

The housing 1 is stamped from a single piece of metal and comprises the top portion 8 parallel with the plate 2 and the substantially vertical sides 9, 9. Any suitable means may be provided for securing the housing to the plate 2, but to conserve metal and labor tongues 10 and 11 are struck upwardly from the plate 2 and these are provided with reduced portions 12 extending through apertures in the top 8 of the housing and upset thereon, thereby riveting the housing securely to the base plate. The housing is of peculiar formation. From end to end the housing, as an entirety, is formed with tapering side walls, as shown by a casual reference to Fig. 1. The taper

is not uniform, however, but is interrupted by surfaces which gradually and collectively form the taper.

As seen in Fig. 3 the taper constitutes substantially two compartments. From the enlarged end to point 14 a receiving compartment exists. It is relatively wide, that is, its walls are spaced apart sufficiently to permit ample room for the cords to pass freely by the locking wheel 24, when the wheel is held within this compartment in the dotted line position, without causing any binding action upon the cords. A second compartment is defined by the surfaces from point 14 to the smaller extremity 13. This is the wedging and locking compartment. From 14 to line α it is abruptly constricted to form shoulders 15 and this constriction is partially relieved by the slightly flared surfaces from lines α and 4 to point 9. This partial relief has the effect of allowing the cords to slightly expand after passing shoulders 15, with the result that a pronounced pressure is created against the flared surface, tending to force the locking wheel toward the smaller end of the housing and thus securely maintain it in wedging position. The smaller end of the housing has its walls parallel as at 13.

16 indicates a slide mounted within the housing 1 and comprising a plate 17 having depending tapered side walls 18 which extend around the outer end thereof as at 19. Said slide is provided with a longitudinally disposed slot 20 through which the tongue 11 extends, said tongue limiting the movement of the slide as indicated clearly in Fig. 3. The inner end of the portion 17 of the slide is provided with an extension or ear 21 having a perforation 22 to receive a trunnion 23 formed on a rotary member 24. To save the cost of labor and materials, the trunnion 23 is preferably formed integral with said rotary member. The rotary member 24 is preferably in the form of a grooved, knurled wheel, and when the slide 16 is moved inwardly, said wheel clamps the bights of the rope 5 between itself and the walls 9 as previously described. When in this position, the rope can not be withdrawn to enlarge the size of the loop 5'. Should sufficient force be applied to withdraw one bight of the rope in the direction of the arrow α , the rotary member 24 compensates for said movement by drawing inwardly a like portion of the rope in the direction of the arrow β . See Fig. 3. Also when the wheel 24 is in the said position, it is impossible to shake the device loose or move the same away from the loop 5' without first withdrawing the slide and said wheel. When withdrawn into the position shown in dotted lines in Fig. 3, the bights of the rope are free to pass readily through the housing so as to

either increase or decrease the size of the 65 loop 5'. While the device is practically adapted for any purpose where it is desired to hold both bights of a rope, it is evident that it is preëminently adapted to use as a mail-bag fastening device. In order to further adapt the same for such use, and particularly with registered mail where the mail pouches are locked, I provide means for securely locking the wedging or compensating wheel 24 in position. For this purpose, the 70 housing 1 is provided at its outer end with an extension 25 provided with an aperture 26, and the outer end of the slide 16 is provided with a corresponding aperture 27 which registers with the aperture 26 when the device is 75 in locking position. These registering apertures are adapted to receive the shackle 28 of a padlock, and it is obvious that with a padlock so positioned therein the rope 5 is securely locked against being tampered with 80 by unauthorized persons.

It is obvious that when the shackle of the padlock is within the apertures 26 and 27 that the slide 17 will have some longitudinal motion inasmuch as the shackle does not 90 completely fill said apertures. The shoulders 15 and the flare α to 9 will normally prevent accidental retractive movement of said slide, but any one tampering with the device may move the slide until the same 95 firmly abuts the shackle of the padlock. To avoid such movement of the slide from moving the wedging member 24 the aperture 22 in which the trunnion 23 is mounted is elongated sufficiently to permit of the above- 100 mentioned movement of the slide without moving the member 24.

When the device is to be used for a rope holder other than that of a mail bag fastener, as, for instance, for awning cords, the flanges 6 and 7 are dispensed with and the plate 2 is used for securing the device in position. Also the extension 25 and apertures 26 and 27 are omitted, as may also be the perforated flange 3.

We claim:—

1. A cord fastener comprising a base plate, a slide movable on said base plate, a locking wheel movable with said slide, a housing fixed upon the base plate having its side 115 walls bodily tapered from end to end to provide two compartments, one wider than the other, the walls being abruptly constricted between the two compartments.

2. A cord fastener comprising a base plate, 120 a slide movable on said base plate, a locking wheel movable with said slide, a housing fixed upon the base plate having its side walls bodily tapered from end to end to provide two compartments, one wider than the 125 other, the walls being abruptly constricted between the two compartments and slightly flared between said constricted portion and

the smaller end of the housing and tapered from said slightly flared portion toward the smaller end of the housing.

3. A cord fastener comprising a housing, 5 a slide movable therein, said housing and said slide being provided with apertures adapted to register and receive the shackle of a padlock, and a locking wheel movable with said slide.

In testimony whereof we have signed our 10 names to this specification in the presence of two subscribing witnesses.
